UNITED STATES PATENT OFFICE.

JACOB COHEN, OF MIDDLE VILLAGE, NEW YORK.

DESIGN FOR A DOLL PURSE.

Application filed January 5, 1928. Serial No. 24,756. Term of patent 3½ years.

To all whom it may concern:

Be it known that JACOB COHEN, a citizen of the United States, and resident of Middle Village, in the county of Queens and State of New York, has invented a new, original, and ornamental Design for a Doll Purse, of which the following is a specification, reference being had to the accompanying drawing, forming part thereof, in which—

Fig. 1 is a front elevational view of a doll purse embodying my new design; and

Fig. 2 is an end elevational view thereof.

I claim:

The ornamental design for a doll purse as shown.

Dated New York city, December 28, 1927.

JACOB COHEN.
